UNITED STATES PATENT OFFICE.

GILBERT EDWARD LOSEE, OF PHILADELPHIA, PENNSYLVANIA.

WINDOW-CURTAIN.

1,331,346.

Specification of Letters Patent. Patented Feb. 17, 1920.

Application filed July 25, 1919. Serial No. 313,156.

To all whom it may concern:

Be it known that I, GILBERT E. LOSEE, a citizen of the United States, and resident of Philadelphia, Pennsylvania, have invented 5 certain new and useful Improvements in Window-Curtains, of which the following is a specification.

My invention consists in the features and combination and arrangement of parts 10 hereinafter described and particularly pointed out in the claims.

In the accompanying drawings Figure 1 is a front view of a curtain arrangement embodying my invention.

15 Fig. 2 is a vertical sectional view of the parts shown in Fig. 1.

Fig. 3 is a front view with the upper border section or ventilating member drawn down into position to provide the desired 20 ventilation at the upper part of the window.

Fig. 4 is a vertical sectional view of the parts shown in Fig. 3.

25 Fig. 5 is a detail view of parts of the blank from which the upper ventilating or border section is formed.

Fig. 6 is a vertical sectional view partly in perspective of the upper border section or ventilating member.

Fig. 7 is a perspective view of one of 30 the brackets.

Fig. 7^a is a similar view of the other bracket.

Fig. 8 is a detail vertical sectional view 35 through the lower portion of one of the brackets showing the rail of the ventilating section engaged therewith in its extended position.

Fig. 9 is a sectional plan view through the lower part of one of the brackets and the 40 window frame with the border member also shown in section.

In these drawings 1 indicates the window frame to which are attached brackets 2 at the upper portion thereof. These brackets are 45 shown in detail in Figs. 7 and 7^a. Each bracket includes a main strip portion 3 with the ears or base parts 4, which latter are perforated to receive holding means such as screws to fasten the brackets to the window 50 frame and each bracket includes also a front portion 5 which extends at right angles to the side portions 3. The front members 5 are provided with counter-sunk portions at 6 terminating in shoulders at 7. The side 55 portions 3 of the brackets have bearings 8

for the upper roller and bearings 9 for the main curtain roller. The main curtain roller may be of the ordinary spring type, for instance such as the well known Harts-horn's. The brackets are also provided with 60 a shield portion 10 which lies in front of the bearings 9 and extends at right angles to the extension 11 of the sides 3 so that these portions 10 will hide or shield from view the ends of the main roller. The upper 65 roller which is mounted in the bearing 8 may be of any ordinary spring type and it carries the border or ventilating member which consists of a sheet of curtain material having openings, as shown in Fig. 5 at 70 12, provided with any suitable form of screen material indicated at 13.

As shown in Fig. 5, the blank is provided with two sets of openings so that when it is folded, as shown in Fig. 6, the openings of 75 the two sets will register and the screen material 13 is held between the two sides or folds of the blank.

A rail 14 is secured to the ventilating or border member at a point intermediate of 80 its height, as shown in Fig. 6, and two flaps or sides 15 and 16 are held apart by the presence of this rail 14. The rail is secured to the border or ventilating member by a strip of material 17 which surrounds 85 the rail and has its upper edges stitched at 18 between the sides of the ventilating member. This rail is of triangular shape in cross section and it holds the flaps 15 and 16 at a sufficient distance apart to allow 90 them to embrace the main curtain roll, as indicated in Fig. 2, this main curtain roll being shown at 19. When the ventilating member is in its uppermost position, as shown in Figs. 1 and 2, the flaps or lower 95 side portions 15, 16, thereof will lie on each side of the main roll so as to conceal the same. The main curtain can be manipulated in the ordinary manner by the curtain pull 20 and a second pull or handle 100 member 21 is provided for manipulating the upper border member. By drawing this down it will, as shown in Fig. 4, be brought to a position where the screen openings will be exposed at the top of the window for 105 ventilating purposes, and when so drawn down it may be held in this position by a catch 22 engaging the lower shoulder 7 of the bracket, as shown in Fig. 8. This will hold the ventilating member in its extended po- 110

sition against the pressure of its winding spring which tends constantly to wind the ventilating member into the position shown in Fig. 2. When in the latter position the 5 catch 22 will engage the upper shoulder 7 of the bracket and maintain the border member in this position with the upper part of the window closed against the passage of air at this point. As shown in Fig. 9, the 10 rail 14 is provided with an extension 23 on its front side and this extension carries the catch pin 22. This catch member forms a lateral extension of a pin 24 which is driven in the edge of the extension 23 and into the 15 main part of the rail, and there is provided a flange 24', Fig. 8, which will resist twisting strain on the catch pin 22, this flange being integral with the pin 24.

I provide a supplemental flap at 25 which, 20 when the ventilating member is drawn down, will come against the window frame and close the crevice between the frame and the upper roller so that insects will be excluded. It will be noted that the upper 25 member winds on the upper roll from the inside of the room and as a result of this when the upper border member is rolled up the screen material will not be exposed to view but will present the appearance of 30 ordinary curtain material. When drawn down the side edges of the upper or border member will lie close against the front flange 5 of the bracket so as to make a close joint therewith to exclude insects or dust, 35 and this close joint is aided or contributed to by the counter-sunk portions 6 enabling the catch 22 to be received therein and allowing the curtain material to come close against the face of the front flange 5.

In both the rolled and extended positions 40 of the upper border member it will act to conceal the main curtain roller and in a large measure it will also conceal the brackets, and in addition to this the extension 45 at the lower ends of the bracket will mask or conceal the ends of the main curtain roller.

The present invention is an improvement 50 upon that disclosed in Letters Patent of the U. S. #1303081 granted to me May 6th 1919.

By my present construction the appliance is simplified and made easier to mount, and is capable of being manipulated more readily.

55 The ventilating curtain simply lies with its side edges against the front faces of the side flanges 5 and when released from the shoulders 7 it may be moved toward the inside of the room to allow access to the upper 60 part of the window for cleaning or other purposes, and it readily may be removed and replaced.

The side edges of the ventilating member are not confined between guide plates but as 65 stated, simply lie upon the front faces of

the flanges 5, but at the same time a closed joint between the side edges and the flanges 5 will be secured.

It will be noticed that the slotted bearing for the curtain roller on one bracket is shown 70 at 9 while the slotted bearing for the other roller is on the other bracket at 8. This reversal or different location of the position of these bearings enables an ordinary spring roll of the Hartshorn type to be used for both 75 the main curtain and the ventilating curtain. When used for the upper position the roller may be converted into an ordinary spring roller by removing the ratchet mechanism.

I claim:—

1. In combination a main curtain or shade, a spring roller therefor, a ventilating curtain, a spring roller therefor, brackets, each having a side plate with bearings for the rollers, and a front flange or plate extending 85 at right angles to the side plates and toward each other in a direction across the window opening parallel with the ventilating curtain, said ventilating curtain bearing upon the front face of said flange, catch means on 90 the ventilating curtain and means on the said flanges to be engaged thereby, substantially as described.

2. In combination a main curtain or shade, a spring roller therefor, a ventilating curtain, a spring roller therefor, brackets each having a side plate with bearings for the rollers, and a front flange or plate extending at right angles to the side plates and toward each other in a direction across the 100 window opening parallel with the ventilating curtain, said ventilating curtain bearing upon the front face of said flange, catch means on the ventilating curtain and means on the said flanges to be engaged thereby, 105 said last mentioned means consisting of shoulder adjacent countersunk portions of the flanges, substantially as described.

3. In combination a main curtain with its spring roller and a ventilating curtain at 110 the top of the main curtain also having a spring roller, brackets having bearings for the spring rollers and each having also a front flange or plate extending parallel with the faces of the curtain and upon the front 115 face of which the curtain rests and a shield member on each bracket extending in front of the main spring roller, substantially as described.

4. In combination a main spring roller 120 with its curtain, a ventilating curtain above the main curtain, a spring roller therefor, brackets each having a side with bearings for the rollers and a front flange extending 125 at right angles to the side and parallel with the face of the ventilating curtain which lies thereon, the side of each bracket at its lower end having an extension reaching forward of the vertical plane of said front flange at a point adjacent to the roller of 130

the main curtain and a shield on said extension reaching to the front of the end portion of the main spring roller, substantially as described.

5. In combination a main curtain and its roller, a ventilating curtain above the main curtain, a spring roller therefor, a rail at the lower end of the main portion of the ventilating curtain, flaps spaced apart by 10 the said rail and depending on each side of the main roller, said rail at its ends being shouldered to leave an extension at each end in line with the front of the rail, brackets having flanges extending in a direction 15 across the window opening and parallel with the face of the ventilating curtain and in front of which the extensions of the rail lie, catch means on said extensions and means on the said bracket flanges to be engaged by the catch means, substantially as 20 described.
6. In combination a main curtain with its roller, a ventilating curtain with its roller arranged above the main curtain, said ventilating curtain comprising a main portion with depending flanges or border sections spaced apart equally on each side of the plane of the main portion of the ventilating curtain, a rail at the junction of the border 25 sections and main portion of the ventilating curtain, said rail having reduced ends with the rear faces thereof, substantially in the plane of the main portion of the ventilating curtain, brackets having flanges which extend toward each other and upon the front 30 faces of which the main portion of the ventilating curtain is adapted to lie, catch means between the rear faces of the rail extensions and the front faces of the bracket flanges, 35 substantially as described.
- 40 7. In combination a main curtain with its

roller, a ventilating curtain with its roller above the main curtain, said ventilating curtain consisting of material doubled upon itself with screen material held between its 45 sides, a rail between the downward continuation of the side portions or folds of the ventilating curtain to space the same apart and form depending border flaps, said border flaps embracing the roller of the main 50 curtain, substantially as described.

8. In combination a main curtain with its roller, a ventilating curtain, a roller therefor, said ventilating curtain consisting of two sheets of material face to face holding 55 screen material and having their lower portions spaced apart to form border sections, a rail for spacing apart the border sections and the strip of material surrounding the rail and forming a pocket therefor, the 60 edges of said strip extending upwardly from the rail and stitched between the sheets forming the main body of the ventilating curtain, substantially as described.

9. In combination a main curtain with its 65 roller, a ventilating curtain above the main curtain, a roller therefor, brackets in which the rollers are mounted, each of said brackets having a flange extending parallel with the face of the ventilating curtain, said 70 ventilating curtain having a rail which is shouldered at its ends providing reduced extensions overlying the faces of the said flanges, catch means between the reduced extension and the flanges, the shoulders on the 75 rail acting as lateral guiding means for the curtain in connection with the edges of the flanges, substantially as described.

In testimony whereof, I affix my signature:

GILBERT EDWARD LOSEE.
